Primary Examiner — Michael A. Pratt*(74) Attorney, Agent, or Firm* — Boyle Fredrickson, S.C.(57) **CLAIM**

The ornamental design for stroller frame, as shown and described.

DESCRIPTION

FIG. 1 is a perspective view of a stroller frame in accordance with the present invention;

FIG. 2 is a front view of the stroller frame of FIG. 1;

FIG. 3 is a back view of the stroller frame of FIG. 1;

FIG. 4 is a side elevational view of a first side of the stroller frame of FIG. 1;

FIG. 5 is a side elevational view of a second side of the stroller frame of FIG. 1;

FIG. 6 is a top view of the stroller frame of FIG. 1;

FIG. 7 is a bottom view of the stroller frame of FIG. 1;

FIG. 8 is a perspective view of an alternate embodiment of a stroller frame in accordance with the present invention;

FIG. 9 is a front view of the stroller frame of FIG. 8;

FIG. 10 is a back view of the stroller frame of FIG. 8;

FIG. 11 is a side elevational view of a first side of the stroller frame of FIG. 8;

FIG. 12 is a side elevational view of a second side of the stroller frame of FIG. 8;

FIG. 13 is a top view of the stroller frame of FIG. 8; and,

FIG. 14 is a bottom view of the stroller frame of FIG. 8.
